BOTTLE

Fred R. High, Attleboro, Mass., assignor to T. J. Holmes Co., Inc., Attleboro, Mass., a corporation of Massachusetts

Application April 22, 1948, Serial No. 145,902

Term of patent 14 years

(Cl. D58—8)

To all whom it may concern:

Be it known that I, Fred R. High, a citizen of the United States, residing at Attleboro, in the county of Bristol and Commonwealth of Massachusetts, have invented a new, original, and ornamental Design for a Bottle, of which the following is a specification, reference being had to the accompanying drawing, forming a part thereof, and wherein Fig. 1 is a side elevational view of the bottle embodying my new design; Fig. 2 is an elevational view of the bottle rotated 45° from its position in Fig. 1; and Fig. 3 is a plan view thereof.

I claim:

The ornamental design for a bottle, as shown.

FRED R. HIGH.
